UNITED STATES PATENT OFFICE

169,674

DISPLAY UNIT

Herbert Hyams, New York, N. Y.

Application August 23, 1950, Serial No. 11,893

Term of patent 3½ years

(Cl. D80--9)

To all whom it may concern:

Be it known that I, Herbert Hyams, a citizen of the United States of America, residing at city, county, and State of New York, have invented a new, original, and ornamental Design for a Display Unit, of which the following is a specification, reference being had to the accompanying drawing, forming a part thereof.

I claim:

The ornamental design for a display unit, as shown.

HERBERT HYAMS.
